UNITED STATES PATENT OFFICE.

PHILIP SACHS, OF NEW YORK, N. Y.

TRANSIT SYSTEM.

Application filed September 8, 1923. Serial No. 661,542.

This invention relates to an improved type and new method of operating a rapid transit system.

The invention has for its object a solution 5 of the rapid transit problem of cities, like New York for example, where economical utilization of the available space remaining for the construction of transit lines must be realized, together with increased carrying 10 capacity. Although the invention is described with reference to the subways, the principles of the invention are applicable wholly or in part to the elevated and surface railway systems.

15 It is an important object of this invention to provide a subway system and method of operation with greatly increased carrying capacity for the space required as compared with the present subways, and to provide a 20 system which can be constructed and operated at less cost than subways of the existing type.

Another object is to provide a more flexible 25 transit system, wherein the location of the stations can be readily and economically changed to accommodate the shifting of the population and business centers.

Another object is to provide a transit system 30 in which the train length can be readily changed without necessitating a change in the tracks, or the structure of the subway or the signal system.

Another object is to provide a subway, or 35 other transit system, with a substantially uniform overall width whereby certain economies in construction and operation are realized.

Other objects of the invention are to reduce 40 the train headway, reduce power consumption and other operating expenses, increase the schedule speed, carrying capacity, operating efficiency and factor of safety, and eliminate or reduce stations and train congestion.

45 Various other objects and advantages will appear as the description of the invention proceeds.

Referring now to the drawings which illustrate a preferred form of the invention:

50 Figure 1 is a diagram illustrating the operation of the new system;

Figure 2 is a diagrammatic plan view of the construction thereof, showing the continuous island platform;

55 Figure 3 is a diagrammatic plan view of a modified form of subway system;

Figure 4 is a cross sectional view of a subway such as is illustrated in Figure 2.

Figure 5 is a cross sectional view of the 60 type of subway now in use.

Figure 6 is side elevation illustrating one 65 way of constructing the subway according to my invention.

Figure 7 is a diagrammatic view showing 70 graphically the economical use of subsurface space.

The urban transportation problem is rapidly 75 gaining in seriousness and importance. On the one hand we are confronted with the rising tendency in the cost of labor and materials entering into construction and equipment and operating expenses of the transit lines, which, in the face of the low fare that is generally demanded, makes the operation thereof unprofitable and investment in new 80 lines unattractive. On the other hand our large cities are rapidly growing in population and expanding industrially and commercially and the riding habit of the inhabitants is as a result increasing, at the same 85 time the motor traffic is also rapidly gaining, making walking unpleasant, hazardous and slow. In other words, while the demand for rapid transit is spreading and growing more urgent the task of meeting it is becoming more difficult. In New York city, 90 for example, the situation is particularly serious for in addition to the huge sums of money that an adequate solution of the problem would call for, a shortage in underground street space is beginning to manifest itself.

Already most of the longitudinal streets are provided with rapid transit lines. If the present rate of growth of traffic continues, a line under every longitudinal 95 street will be inadequate in the course of about ten years. The building of additional subways of the present type would afford relief of only a temporary nature, but would at the same time cause permanent harm, as 100 it would tend to exhaust the city's finances, use up the city's streets, and burden the city with the payment of interest on an investment that according to present indications may never become self-supporting.

105 What we need then, is not more subways, but subways of a better type, subways that will cost less to construct, equip and operate

than the present ones and provide a greater capacity. These requirements are met to a remarkably large extent and many additional and important advantages are gained through my invention herewith described, which consists in the introduction of simple changes in the construction and operation of new lines which would cost but little or nothing to effect. Two main features will be discussed here; one relating to the type of the structure of my invention, and one relating to the operation of the new system.

Construction.

15 The present rapid transit system may be regarded as a compromise between the trolley and trunk line railroad. When the trolley became too slow, and its capacity too inadequate for the rapidly expanding, rapidly 20 growing population, a rapid transit system was devised to operate on a private right of way, and to stop at fixed points like a trunk line, but make these stops frequent enough to suit an urban population. In designing 25 the structure for this system, however, two important points were either overlooked or thought unnecessary to consider at that time:

(1) While the capacity of the trunk line 30 is only limited by its train headway, the capacity of a rapid transit system is limited by its train length which, in turn, is fixed by the length of station.

(2) While in the case of the trunk line, 35 new stations can be built and old ones removed or shifted to meet new conditions, in the case of a rapid transit system, this cannot readily be done.

40 The result has been a system sadly deficient in flexibility, elasticity and adaptability to new conditions, so essential to the success of any device providing transit for a rapidly growing city.

In order to meet the demands of the 45 increasing population and shifting business and residential centers of our growing cities, a transit system should provide ready means for increasing its capacity by increasing the train length and for relocating its 50 stations as the business and residential centers shift. The present subway system is deficient in these respects because the platforms are built to accommodate only a certain length of train, and each time a car is 55 added to the train every platform on the line must be correspondingly lengthened, and in case the tracks are curved at the platform, as at island platforms, the tracks must also be changed. To change the location of a 60 station it is necessary to construct an entirely new station with new loading platforms, new entrances, etc., and to destroy the old station, all of which involves a great expense.

65 In order to overcome these and other ob-

jections and provide the desired flexibility, I propose to construct a subway or other transit system with a continuous station platform for the entire length of the line whereby train lengths can be increased to an 70 indefinite degree; and the stations or loading platforms, relocated or changed at will without expense.

An embodiment of this construction 75 wherein the continuous platform is illustrated as being between the tracks, is shown diagrammatically in Figure 2, in which the numerals 1 to 24, etc. represent cross streets. The street C in which the subway is located is shown as being wider than the cross 80 streets to more clearly illustrate the construction of the subway, however, the street C need not actually be any wider than the cross streets 1 to 24 etc. The continuous center platform is designated by the letter 85 D, and it is subdivided by suitable markings such as lines d into the alternate stations A', A'' and B', etc. The up track t and down track t' are located at each side of the platform D and are substantially 90 straight throughout their lengths. Stairways d' at frequent intervals, at and between stations, provide entrance and exit for the platform. It is at once apparent that with such a system no change in the platform is 95 necessary when the trains are lengthened and that it is only necessary to change the markings d to relocate the stations. It will also be shown that track for track this construction will involve little or no additional expense, and when the capacity of the lines is 100 compared will show a great economy over the present system.

In the New York subways for example the local stations now average eight blocks apart 105 and are about two blocks long. The platforms then occupy 25% of the length of line. Since there are two platforms to a station, i. e. one on each side of the tracks, it follows that if we could stagger the up- 110 and-down stations, or place them end to end on an island platform instead of on the opposite sides of the same street, they would occupy 50% of the length of the line or, if they could be made continuous, would leave 115 only 50% of the width of the platform to be accounted for in constructing a subway with a continuous island platform. In other words, the space now utilized for loading platforms if properly distributed would provide a continuous platform of about 50% 120 the normal platform width. The other 50% may be gained without increasing the overall width of the system by utilizing certain clearances in the new type of subway which 125 are now wasted. The clearances now wasted, but which can be utilized in my new construction, are indicated by the dash lines in Fig. 7. They comprise the spaces indicated at M which can be gained by removing the 130

duct benches Y found upon both sides of most of the present subway lines, and which now serve as an emergency walk for the passengers in case a train is stalled between stations, and placing the ducts or cable conduits under the center platforms as illustrated in Fig. 4 and Fig. 6, and the spaces indicated by N plus the width of the spaced center columns X which may be gained through the reduced amount of clearance required between the center line of the tracks and a platform as compared to the clearance required between the center line of the tracks and the face of a column.

To consider a specific example of certain of the New York subways illustrated in Fig. 5, in the case of cars now in use, the distance from center line L of the tracks T to inside face of the wall W is 7' 3", and that to center of interior column X is 6' 6", making a total of 13' 9", or net inside width of a two-track structure of 27' 6". The inside width at stations averages 46' 7" and since the stations occupy about 25% of the total length of line, the average width of the structure is

$$\begin{aligned} .75 \times 27' 6'' &= 20' 7\frac{1}{2}'' \\ .25 \times 46' 7'' &= 11' 7\frac{3}{4}'' \end{aligned}$$

30 Total, 32' 3 $\frac{1}{4}$ "

Under the new system illustrated in Figs. 4 and 6 with the duct benches Y removed from the sides we shall require 6' 3" from center line L' of tracks to inside face of wall W', and 4' 9 $\frac{1}{2}$ " to edge of platform D or a total of 22' 1" for the two tracks, leaving 10' 2 $\frac{1}{4}$ " for a continuous platform D, without increasing the average width of the subway.

By this system the space for the platform D is then gained from the three spaces of the present system; that is, from the space now taken for the present stations, the space M now taken by the duct benches Y and the space N gained by the reduced clearance required from the center line of the tracks to a platform as compared to the space required from the center line of the tracks to the face of a column.

The width of platform D could of course be increased if the 10' 2 $\frac{1}{4}$ " is found insufficient by slightly increasing the overall width of the system.

Suitable entrances and exits for the continuous center platform may be provided in various ways, for instance the subway may be constructed at the edge of the building line, where the platform may be brought under the outer edge of the sidewalk, and entrances constructed there; or a walk may be provided in the center of the street, and frequent entrances constructed from there; or the present type of overhead mezzanine or underground entrances may be provided.

An overhead mezzanine type of entrance is illustrated by way of example in Fig. 6. In this instance the mezzanine C' extends for the width of the structure or any portion thereof over the platforms D and over the tracks, and stairways d' lead from the mezzanine C' to the platform D. The usual type of entrance to the mezzanine C' may be constructed at each side of the street. The mezzanine C' may be continuous with the platform D or may be discontinuous but located at frequent intervals over the stairways d' at or between stations.

As it is usually necessary to excavate to the depth indicated to allow proper entrances to the platform D, it will involve very little additional expense to construct continuous mezzanines C' over the tracks in which case they may be used to supplement the sidewalks or for stores or various other purposes.

By having frequent entrances to the continuous mezzanine C' or to the continuous platform D, the walk to and from stations may be made underground, whereby the passengers may walk to and from their destinations without interference from street traffic.

Due to its substantially uniform overall width, this type of continuous platform subway will be simpler than the present one and the work of designing, constructing and supervising construction much simplified. The elaborate station of the present type and its approaches could be dispensed with for all that is needed is a series of narrow stairways leading directly to the platform D or to the mezzanine C' with either man- or passimeter controls. In view of these economies the new type of subway with a continuous platform can be built without incurring additional expense as compared with the present types, but at a substantial saving when the increased capacity of the new type is considered.

Another advantage of my system is the added safety and security that will be gained by the travelling public through the fact that they are always alongside a platform and not far from an exit; and that if anything happens to a train they are on, they can be let off immediately instead of having to be shut up in a tube, probably dark and smoke-filled, for a long period, or be obliged to brave the third rail.

Operation.

The present local-express system, while highly desirable from the standpoint of economy of operation, and as a convenience to the travelling public, does not work out so satisfactorily from the standpoint of maximum capacity for the following reasons:

1. The local and express trains are as a rule not operated independently, but are

made to supplement each other for a single ride by passengers changing from one to the other at express stations. Inasmuch as the tendency of this transfer is generally in one direction, the effect of it is to overcrowd one system at the expense of the other. An observation of conditions at almost any point of such a system will show that while neither express nor local trains lack in patronage, one, usually the express, always is very much more crowded than the other; and if the degree of congestion of the former be taken as 100%, the other would be only 50% full. The result is that while we operate a 4-track system, we have as far as capacity is concerned, no more than, say a 3-track line.

2. With practically 100% of the local traffic changing for the express at express stations, these stations become over-congested which results in great confusion and delay, and a general upset of schedules.

To increase the carrying capacity and gain other important advantages, I propose to dispense with local and express trains and to operate all trains on the basis of alternate trains making alternate stops. In other words, every A train, A¹, A², etc., will stop at the A stations indicated in Fig. 2 and skip the B stations, while the following B trains, B¹, B², etc., will reverse the process and skip the A stations. By bringing the stations somewhat closer together than they average now, and taking advantage of the end controls or entrances, the maximum walk between the alternate A or B stations would not be much greater than under the present system, at the same time the schedule speed and carrying capacity of the railroad under the skip stop method of operation will materially improve.

The first effect of this method of operation would be to reduce the headway. The train headway is composed of two elements—(1) running headway and (2) station headway. The running headway is the time interval between corresponding points of two trains moving at maximum speed; the station headway is the additional loss of time due to stopping at stations. Under the most exacting requirements of the block signal system, trains can be run at one minute intervals with absolute safety. The station stops, however, impose a loss of another minute composed as follows:

	Seconds.
Acceleration	14
Deceleration	9.2
Station stop	30
Miscellaneous	6.8
 Total	 60.0

By adopting the alternate skip stop method of operation here suggested, the headway can be reduced by 30 seconds, for the station headway loss will be divided by two trains

instead of being borne by one, as is the case in the present system.

Thus if the train A¹ stops at station A', then the corresponding point of train B¹ following, will pass the same point in two minutes. If this train should also stop at the station A', then train A² will pass the same point two minutes later. If however, train B¹ passes through the station A' at full speed without stopping, then train A² will only have to be separated from train B¹ by the running headway which is one minute and will pass by the station A', three minutes after train A¹, instead of four minutes after. In brief, by this method of operation, the time interval between any alternate trains is equal to twice the running headway plus one station headway.

This method of operation may also be used to furnish us with the equivalent of a reservoir, or double track loading station, without the objectionable features of turn-outs, short radii curves, costly approaches and extra tracks. Like a reservoir station this method will permit two consecutive trains on the same track to load and unload at the same time and the headway will generally be determined by the running headway, rather than the station headway.

The operation of this system is shown on the accompanying diagram of Fig. 1, in which horizontal dimensions represent distance and vertical dimensions, time. Each horizontal space represents 250 feet, or one block, and each vertical space represents 20 seconds. Stations A' B' A'' B'' are indicated by heavy lines on the bottom of the diagram. These are indicated on the diagram as being two blocks long and six blocks apart. The diagrams represent train performances and are based upon the following:

Maximum speed 35 miles per hour.

Acceleration 1.25 miles per hour per second.

Deceleration 1.9 miles per hour per second. Station stop 30 seconds.

Trains are designated A¹, A², B¹, B², etc. A trains will stop at A stations, and B trains at B stations. In practice they will similarly be designated and passengers boarding an A train will know from experience or from lists posted in every car, and at frequent intervals in the station where the trains will stop.

Capacity.

Under the present methods of operation in the New York subways, for example, 10-car express trains, and 6-car locals are operated normally on each of the trunk lines. However, not all the cars are operated on a basis of 100% capacity, because the local trains which act merely as feeder for the express trains, are usually only 50% full, and we get ten express cars and three effec-

tive locals, or a total of thirteen cars. At two minute headway, we get a total capacity for two tracks.

5 $13 \times 30 = 390$ cars per hour.

Under my new system, operating under a 90-second headway basis, we shall get on one track, a capacity of

10 $10 \times 40 = 400$ cars per hour.

The capacity of 400 cars per hour on one track, however, merely represents the initial capacity of a highly elastic system, which capacity could be increased almost 10% by 15 merely adding one car to the train, no increase in the station length being necessary, if we have a continuous platform as above described. A two-car addition would mean almost a 20% increase, and by the time a 20-car train is reached, we shall practically have double the capacity of a four-track system on a two-track line, and a 20-car train by no means represents the limit of the continuous platform system.

25 *Signal system.*

A signal system which may be used in the new construction and method of operation is shown diagrammatically on the upper 30 portion of the diagram of Fig. 1. The system here illustrated conforms in essence to all requirements of a standard system.

A block length is composed of two overlaps, each overlap consisting of no less than 35 a braking distance.

At the entrance to each overlap there are two signals, one home, indicating the condition of the track in the same block and one distant, showing the condition of the track 40 in the block ahead. A train is thus always protected by three signals, two home, or danger, and one distant, or caution. It will be understood, of course, that these signals are operated by suitable electric circuits, 45 controlled automatically by the trains.

In Figure 1 home signals are indicated by X^1 , X^2 , X^3 , etc., and distant signals by Y^1 , Y^2 , Y^3 , etc. With train #1 occupying overlap D, home signals X^2 and X^3 will be 50 set for danger and distant signals Y^1 , Y^2 and Y^3 for caution. Train #2 following will find the signal X^1 clear and the caution signal Y^1 effective to indicate caution and the train will be permitted to proceed at a 55 reduced speed to the entrance to overlap C, where the signal X^2 will indicate danger and the train forced to come to a standstill or be tripped on passing the signal.

The workings of the signal system are 60 shown on the train curves. When the train A^2 enters overlap C¹ at point "a", it sets up a danger signal, which position is determined by the intersection of this space point with the corresponding time point "120". 65 This position is at "b". This signal will re-

main up until the end of the train has cleared the forward end of the overlap at "d". Since the train is 500 feet long, the forward end of the train will at that time occupy position "e", corresponding to 140 on 70 the time scale, see "e". Projecting this point to intersect with space point "a" at "f" we get "bf" as the danger signal for the time any portion of train A^2 occupies overlap C¹. While the train occupies overlap D, another 75 danger signal will be set up at the same location shown on the diagram as "gh". While the train occupies overlap E, a caution signal will be set up shown by "kl". In a similar way, all the other signals have been 80 constructed. It is thus seen that at any point there are two danger signals indicated in full line, and one caution signal indicated by dotted lines separating two moving trains, and that there is an additional 85 interval of time between the forward end of a moving train and the nearest caution signal ahead. For convenience of plotting, the length of overlap was taken as 500 feet, which represents the braking distance plus 90 about 10%. It will be seen from the diagram that a considerably longer block could be used for the conditions under consideration without detrimentally affecting the 95 train headway.

A further examination of these curves will disclose some interesting features in the operations of the proposed system. In the first place, we see that we can have a standard block signal system on local tracks that 100 will operate with perfect freedom, without the constraint that is now felt at express stations, without reducing the block length at stations and without having to resort to the time control signals. It might be thought 105 at first that the reduction of the headway from two minutes to ninety seconds, would place the operation under a strain. That the reverse is true is evident from what was just brought out. This property would 110 impart resiliency to the system, and in case of one train being delayed the rest of the system will not be affected by it as quickly as under the present system.

Another important feature of my invention 115 will be seen from the following analysis. By moving the station through one complete block, it can be seen by inspection that the train curves would still clear the signals, except at one point. Referring to curve B¹, it will be noted that a slight movement of station B' to the right would cause the train curve to cut caution signal "mn". While from the standpoint of safety, there 120 is nothing objectionable to a train's entry into a caution zone, from the standpoint of economy of operation, it generally is objectionable, as the slowing down and speeding up again in result is a loss of time and energy. In our case, however, there would 125 130

be nothing objectionable to it from either standpoint, for the train on entering the caution zone will be under full control of the brakes, and on the road to a complete standstill, so that no further speeding up will be required. This means that we shall be able to lay out a system for the new subway at random with nothing but the braking length to be guided by and then lay out our station where we choose, and still be able to maintain our 90 second headway. Similarly, we shall be able to relocate a station without having to change the signal system.

15 *Power consumption.*

Under the skip-stop system the reduction in the number of stops can be made about 40% less than in the present system without increasing the walk to and from stations. 20 Inasmuch as the acceleration consumes about 80% of the total power necessary to operate the local trains, it follows that by reducing the stops 40% we would save more than 30% of the power that is now consumed. 25 Another source of economy in the power consumption is as follows: Under this system with a block signal as described a train at a station will not receive a clear signal until the train ahead has cleared the next 30 station ahead. This means that a motorman on receiving a clear signal at the station will be sure to find a clear road to the next station, and he will therefore be able to accelerate to full speed, coast and apply 35 the brakes without having to repeatedly stop and start as is often the case at present. This will practically eliminate all stops between stations as a result of traffic congestion and, in addition to other advantages, 40 will result in a further reduction in the power consumption. A total saving of 50% in the power consumption as a result of these two features is not impossible.

45 *Power plant capacity.*

As a result of reducing the power 50% as above, the power plant capacity may be correspondingly reduced.

A further reduction in the power plant 50 capacity made possible by the skip-stop method of operation will become apparent from an examination of the diagram of Fig. 1. It will be seen that in a stretch extending over five stations, or about 625 55 feet, the accelerating periods P are uniformly scattered over the entire stretch, each lasting about 36 seconds, and by spacing the sub-stations in such a way that each will feed about 6250 feet of line or any multiple 60 thereof, we would get a practically uniform load on the sub-stations and power plants, with the maximum load but little above the average.

It is of course not essential that the station platform be literally continuous, and in

places where cross-overs are required or natural obstructions present, it may be continued as an overhead or underground walk, or be omitted altogether.

An improvement which may be utilized 70 when desired is a "transfer station", where trains from both the "A" and "B" systems would stop, and passengers would be able to change from one system to the other. This station may be an individual island 75 platform with reservoir tracks, or else a portion of the regular platform with trains from the two systems stopping end to end, and passengers walking the length of the train forward or backward as the case may 80 be. A side transfer platform may also be constructed in special cases. In either case, the same number of passengers will, on an average change from the "A" to the "B" system, as from "B" to the "A" system, 85 and no undue congestion will be produced. In this way every station on the line would be made accessible to all passengers, and the walking to and from the stations reduced.

If one main line is to branch out into two 90 lines in the outlying districts, then each of these lines may either be operated as one "A" and one "B", or else have "A" and "B" trains alternate on each.

The invention has been described as applied to a two track system, and as the capacity of the two tracks with a 20 car train will substantially equal the present capacity of an 8 track system it will probably not be necessary to increase the number of tracks. However, it could be equally well applied to any number of tracks, for example, in Fig. 3, a four track system is illustrated wherein the local tracks F and G are located in the center of the street 100 at each side of the continuous platform C and the express tracks H and I are located at the edge of the street outside the local tracks, suitable platforms E' and E'' being provided outside the express tracks with 105 mezzanine or underneath passages where passengers may transfer from one platform to the other. The express trains K may also be operated upon the alternate skip-stop system so that passengers from local A trains 110 may transfer at stations E', and passengers from B trains may transfer at stations E'', or each express train may make every express stop as under the present systems. In lieu of a four track system with both express and local trains, the four tracks may be operated as two separate two track local systems of the type previously described, by providing a continuous island platform between each pair of tracks, or one of the two track continuous platform systems may be 115 operated as a local system and one as an express system.

Due to the skip-stop operation and the reduction in the number of stops and in the 120

train headway, the operation of the system may be speeded up so that the speed of the skip-stop local trains compares favorably with the speed of the present express trains, giving as one result of my invention a two track system with a carrying capacity practically equal to the present four track system and a speed practically equal to the express train speed of the present system. 10 This feature may also be used in the operation of elevated and surface transit systems.

While the invention has been described as a combination of the continuous island platform with the skip-stop method of operation, which is the preferred embodiment of the invention, it is to be understood that the continuous platform could be used with the present method of operation or that the skip-stop system could be used without 20 the continuous platform and it is my intention to include these and other modifications of my invention within the scope of the appended claims.

What I claim is:

25 1. A method of rapid transit subway railway operation for multiple car trains which comprises stopping alternate trains at alternate stations arranged along a continuous platform.

30 2. A method of rapid transit subway railway operation for multiple car trains which comprises stopping alternate trains at alternate stations arranged along a continuous island platform.

35 3. A rapid transit subway system for multiple car trains characterized by the use of a continuous island loading platform, whereby the locations of the stations may be readily changed.

40 4. A rapid transit subway system for multiple car trains characterized by the use of a continuous loading platform, whereby the length of trains operated is unlimited.

45 5. A rapid transit subway system for multiple car trains characterized by the use of a continuous loading platform constituting a series of stations, and frequent entrances at and between stations.

50 6. A method of rapid transit railway operation which comprises stopping alternate local trains at alternate local stations and alternate express trains at alternate express stations, and stopping all trains at some stations whereby universal transfers may be made.

55 7. A method of rapid transit railway operation which comprises stopping alternate local trains at alternate local stations arranged along a continuous platform and alternate express trains at alternate express stations and stopping all trains at some stations whereby universal transfers may be made.

60 8. A method of rapid transit railway operation which comprises stopping alter-

nate local trains at alternate local stations arranged along a continuous island platform and alternate express trains at alternate express stations and stopping all trains at some stations whereby universal transfers may be made. 70

9. A method of rapid transit railway operation which comprises stopping alternate local trains at alternate local and express stations and stopping express trains at all express stations. 75

10. A rapid transit system characterized by the use of a continuous island loading platform between local tracks, and separate loading platforms outside the express tracks. 80

11. A rapid transit system characterized by the use of a continuous loading platform in the center, local tracks at each side of the platform, express tracks at each side of the local tracks, and loading platforms at 85 intervals outside the express tracks.

12. A rapid transit system characterized by the use of a continuous island platform, local tracks at each side of the platform, express tracks outside the local tracks and parallel therewith, and express stations outside the express tracks whereby the tracks may be approximately straight and no change in the tracks is necessitated by changing the length of stations. 90

13. A subway system of substantially uniform width having a substantially continuous loading platform and substantially straight tracks on either side thereof. 95

14. A transit system including continuous loading platforms constituting a series of stations and a signal system arranged to automatically maintain two danger signals and one caution signal between trains and also arranged to permit the location of the stations to be changed without interfering with the operation of the signal system. 100

15. A method of increasing the carrying capacity of a rapid transit system which comprises stopping alternate trains at alternate stations, whereby the train headway is reduced, and using continuous platforms with substantially straight tracks whereby the train length may be readily increased. 110

16. In a transit system, a plurality of stations, so spaced that a train leaving one of said stations without restraint would endanger a train standing at the next station in advance, and a signal system comprising means controlled by the presence of a train at the advance station to maintain a warning signal at the other of said stations whereby signal stops between stations are ordinarily avoided. 115

17. A transit system comprising a succession of stations for use by alternate trains on the same track, said stations being so spaced that the deceleration and stopping of a train at one station will prevent the movement of said train into dangerous proximity to a 120

train in the block of the next station in advance, whereby the station retardation of said trains may be overlapped to enable the station headway between trains to be reduced 5 for heavy traffic, and a signal system comprising means controlled by the presence of a train at the advance station to set a warning signal in the block of the second station.

18. A rapid transit system in which alternate trains stop at alternate stations, said system being divided into signal blocks each block including a danger signal and a warning signal, the signals being so arranged that the presence of a train at one station will 10 cause a warning signal to be set at the next preceding station so that the checking of speed required by the warning will coincide with the scheduled stopping for the station.

19. A rapid transit system in which alternate trains stop at alternate stations, said system being divided into signal blocks of substantially equal length, each block including danger and warning signals at its entrance and danger and warning signals mid-way between its ends, controlled by the presence of trains in the block and in the blocks in advance so as to maintain two danger signals and a warning signal between trains, the blocks being of a length corresponding substantially to double the safe braking distance of a train, the arrangement of the signal system being such that the stations can be located at any desired distance apart so long as each station is spaced from the sta-

tion in advance of it at least far enough to 35 have two danger signals and a warning signal interposed between trains at said stations.

20. A method of transit operation which comprises running a succession of trains on the same track with less headway than the sum of the time required for a station stop and the necessary running headway, and stopping alternate trains at alternate stations whereby the station retardation of the successive trains is overlapped and retardation of trains by those preceding them is ordinarily avoided.

21. In a transit system, the combination with a plurality of stations, of a signal system comprising a series of blocks arranged in overlapping relation, each block being equal in length to double the safe braking distance of a train, and each block being overlapped by two adjoining blocks which meet at its 55 middle so that the track is divided into block overlaps equal in length to the safe braking distance of a train, the arrangement being such that a train is always in two overlapping blocks, each block having a 60 danger signal and a caution signal at its entrance made effective by the presence of a train in the block, the caution signal being also made effective by the presence of a train in the advanced overlapping block.

In testimony whereof I have affixed my signature to this specification.

PHILIP SACHS.

Certificate of Correction.

Patent No. 1,616,554.

Granted February 8, 1927, to

PHILIP SACHS.

It is hereby certified that error appears in the printed specification of the above-mentioned patent requiring correction as follows: Page 7, line 106, claim 14, for the word "charged" read *changed*; and that the said Letters Patent should be read with this correction therein that the same may conform to the record of the case in the Patent Office.

Signed and sealed this 8th day of March, A. D. 1927.

[SEAL.]

M. J. MOORE,
Acting Commissioner of Patents.
